UNITED STATES PATENT OFFICE.

ELMER C. DITTMAR, OF WILLIAMSPORT, PENNSYLVANIA, ASSIGNOR TO THE CROOKS-DITTMAR COMPANY, OF WILLIAMSPORT, PENNSYLVANIA, A CORPORATION OF PENNSYLVANIA.

MACHINE FOR FINISHING FLOORING.

Application filed July 31, 1919, Serial No. 314,465. Renewed November 11, 1922. Serial No. 600,477.

To all whom it may concern:

Be it known that I, ELMER C. DITTMAR, citizen of the United States, residing at Williamsport, in the county of Lycoming and State of Pennsylvania, have invented certain new and useful Improvements in Machines for Finishing Flooring, of which the following is a specification, reference being had therein to the accompanying drawing.

This invention relates to a machine for finishing flooring, and is a companion application of my application Serial No. 314,464 filed July 31, 1919, the object of the present invention being to provide means for applying a coat of varnish to the strip of flooring which has been filled by the above mentioned machine and allowed to dry.

Another object of my invention is to provide a construction of apparatus which is substantially the same as shown in my companion application, with the exception that the parts are re-arranged and additional parts are added in order to carry out the method of varnishing a strip of flooring so as to apply a smooth surface.

At still further object of the invention is to provide a novel form of polishing device for polishing the surface before the coating of varnish is applied.

Other and further objects and advantages of the invention will be hereinafter set forth and the novel features thereof defined by the appended claims.

In the drawings:

Figure 1 is a side elevation of an apparatus constructed in accordance with my invention.

Figure 2 is a top plan view of the delivery end of the apparatus shown in Fig. 1.

Figure 2^a is a top plan view of the feed end of the apparatus.

In the drawing 1 indicates a frame provided with driving mechanism constructed substantially as shown in my companion application, Serial No. 314,464, and provided with a guideway 2 constructed identically as shown in the above referred to application. The guideway is adapted to receive a strip of flooring 3 which has been previously coated with a filling composition and is moved continuously through the guideway by feed rollers 4 and 5 held in contact with the opposite faces of the strip by mecha-

nism constructed identically as shown in the machine for filling the strip, which mechanism consists broadly in arms 6 and 7 connected to a crank carried by a rock shaft by links, said rock shaft having a weighted arm 8 connected thereto to which is connected a lever 9, by means of which the weighted arm can be raised so as to move the feed rollers 4 and 5 out of contact with the strip. The feed rollers 4 and 5 are revolved through the medium of gears 10 which mesh with gears 11 carried by shafts 12, one of said shafts being provided with a bevel gear 13 meshing with pinion 14 carried by a shaft provided with a pulley over which passes a drive belt from a driven shaft 15, the above construction being described broadly so that the operation will be clearly understood.

Arranged to one side of the guideway 2 is a plurality of rollers 16 which are adapted to engage one face of the strip of flooring so as to hold the same against lateral pressure. Arranged opposite the rollers 16 is a circular polisher 17 which comprises a disk having a coiled fabric 18 secured to the face thereof which is adapted to engage the face of the strip of flooring so as to polish the surface before the coat of varnish is applied. The polisher 17 is carried by a shaft supported by a carriage 19 mounted on a suitable guideway 20 which is adjusted therein by a hand wheel 21 whereby the polisher can be adjusted in respect to the face of the flooring strip so as to apply the proper pressure as the same is revolved. The shaft of the polisher carries a pulley 22 over which passes a belt 23 extending from a pulley carried by the driven shaft 15, the construction of driving means and support for the polisher being substantially the same as that shown in my companion case used for supporting the circular wiper.

The upper bearing for one of the shafts 12 carries a split collar 24 having an extension to which is connected an arm 25 provided with a bearing 26 in which is mounted a shaft 27 carrying a brush 28 for removing the dust formed by the polisher so that the strip of material will be thoroughly cleaned before it reaches the varnishing device. The shaft 27 carries a pulley over which extends belt 29 which is driven by a pulley carried by one of the shafts 12, this construction

being substantially the same as that shown in my companion application.

The guideway is cut away, and secured over the cutaway portion is a receptacle 30 which is identical in construction with the filler receptacle shown in my companion application designated Serial No. 314,464, and is provided with a discharge opening over which the strip of flooring is adapted to pass 16 so that the previously filled surface will be given a coat of varnish, the movable guideways and pressure bars contacting with the surfaces of the strip so as to prevent the escape of varnish from the receptacle around 15 the discharge opening thereof.

As the strip of flooring moves past the varnish applying receptacle it is brought into contact with a series of brushes 31 which are supported by portions 32 secured 20 to the guide members of the guideway, so as to give an even flow to the varnish or spread the varnish evenly upon the surface of the strip.

From the foregoing description it will 25 be seen that I have provided an apparatus for finishing flooring, having means for applying the first coat of varnish to the previously filled surface, by means of which I am able to use a construction of apparatus 30 substantially the same as that shown in my above application designated Serial No. 314,464 with the exception that the polisher is arranged in advance of the liquid applying receptacle, and the series of brushes 35 are arranged to apply the varnish for spreading and forming a smooth surface.

In the operation of the apparatus as herein shown for applying the first coat of varnish to a strip of flooring which has been 40 previously filled, the strip of flooring which has been passed through a filler machine is forced into the guideway and the feed rollers force the strip to move continuously in their passage through the machine, and the partly 45 finished surface of the strips is polished, then cleaned, and then coated with varnish, which varnish is spread evenly over the surface by a series of stationary brushes so that when the strip is discharged from the 50 machine it will be given an even coating of varnish.

In the drawings I have shown an apparatus for applying and finishing only one 55 face of a strip of lumber in its passage through the machine, but it is of course understood that the members for applying the coating of varnish and finishing the same could be duplicated so that both faces of the strip would be finished in its passage 60 through the machine, and while I have described the operation of the apparatus in coating and finishing a strip of flooring, I do not wish to limit myself to the finishing of any particular kind or form of strip, as 65 wainscoting or molding could be varnished

or finished in an apparatus having a guideway conforming to the shape of the edges of the strip to be finished.

The main object of my invention is to provide an apparatus with novel means for 70 coating and polishing so as to eliminate the use of manually operated means for obtaining the desired result, and I have found in practice that a strip can be highly polished without the use of sandpaper. 75

What I claim is:

1. An apparatus for applying a coat of varnish to a strip of flooring which has been filled, consisting of means for moving a strip of flooring continuously in a guideway for supporting the same on edge, means for polishing the face of the strip in its passage through said guideway, means for causing said strip in its passage through said guideway to move over the discharge 80 opening of the varnish containing receptacle, and a series of brushes arranged in the path of travel of said strip for spreading the varnish applied by the receptacle. 85

2. An apparatus for varnishing a strip 90 of lumber comprising a guideway for supporting and guiding a strip of lumber on edge in its passage therethrough, means for moving the strip continuously, a revolving polisher arranged in the path of travel of said strip for polishing one face thereof, a revolving brush for cleaning the strip, a receptacle having a discharge opening over which said strip passes for applying a coating of varnish thereto, and a series of stationary brushes arranged in the path of 100 travel of said strip. 105

3. An apparatus for finishing flooring, having a guideway for supporting and guiding a strip of flooring on edge in its passage therethrough, a pair of feed rollers for engaging the opposite faces of said strip for moving said strip through said guideway, a revolving polisher adjustably mounted in respect to one face of said strip, a receptacle having a discharge opening over which said strip is adapted to pass for receiving a coating of varnish, and stationary brushes for spreading the coating of varnish arranged in the path of travel of said 110 strip. 115

4. An apparatus for finishing flooring, having means for supporting and moving the strip of flooring on edge, means for polishing one face of the strip, and means for 120 coating one face of the strip.

5. An apparatus for varnishing a strip of lumber, having means for moving a strip of flooring continuously on edge, means for polishing one face of the strip, a receptacle having a discharge opening over which said strip is adapted to pass to receive a coat of varnish, and means for spreading the coating of varnish received from said receptacle. 125

6. An apparatus for finishing flooring, 130

- comprising a guideway for supporting and guiding a strip of flooring on edge, feed rollers arranged to engage the opposite faces of said strip for moving said strip in said 5 guideway, a revolving adjustably mounted polisher arranged in the path of travel of said strip, a varnish containing receptacle having a discharge opening arranged to apply a coat of varnish to one face of said 10 strip in its passage thereby, and a stationary brush arranged in the path of travel of said strip for spreading the varnish previously applied.
7. An apparatus for varnishing a strip of 15 lumber, comprising a guide way for supporting and guiding a strip of lumber on edge in its passage therethrough, means for moving the strip in said guide way, a polisher arranged in the path of travel of said strip 20 for polishing the face thereof, a brush for cleaning the strip, a receptacle having a discharge opening over which said strip passes for applying a coating of varnish thereto and a brush arranged in the path of 25 travel of said strip for spreading the varnish applied by said receptacle.
8. An apparatus for finishing strips of
- lumber having means for supporting and moving strips of lumber on edge, a revolving polisher for polishing the side faces of 30 said strips while in motion, means for coating the face of the strip while in its passage through said supporting means and means arranged to one side of said supporting means for spreading the coating applied to 35 said strip.
9. An apparatus for finishing flooring or the like comprising a guide way for supporting and guiding a strip of flooring on edge, means for moving a strip of flooring in said 40 guide way, an adjustable revolving polisher arranged to one side of said guide way and adapted to engage one face of the strip in its passage therethrough, means disposed to one side of said guide way for applying a 45 coating to the face of the strip in its passage through said guide way and means for spreading the coating applied.

In testimony whereof I hereunto affix my signature in the presence of two witnesses.

ELMER C. DITTMAR.
